Charles E. Wilson
ATTORNEY.

UNITED STATES PATENT OFFICE.

EDWARD W. N. BOOSEY, OF DETROIT, MICHIGAN.

CLOSET FLANGE.

Application filed August 28, 1924. Serial No. 734,625.

This invention relates to closet flanges utilized in connecting a closet bowl or similar fixture with the drain pipe, and the object of the invention is to provide a flange for the purpose stated permitting a ready connection of a closet bowl with the drain pipe which may vary as to the position of the upper end relative to the floor surface, and further to provide a construction in which a member is provided adjustable longitudinally of the drain pipe to receive the horn of the closet bowl and carrying an adjustable flange by means of which the bowl may be fixedly secured to the piping. Another object of the invention is to provide an adjustable member to accommodate different lengths of horns for the closet bowls and providing a packing between the horn and the drain connection to prevent leakage between the flange and the bowl. These and other objects and the several novel features of the invention are hereinafter more fully described and claimed, and the preferred form of construction of a device embodying my invention is indicated in the accompanying drawings in which—

Fig. 1 is a vertical section showing the lower end of the closet bowl and my improved construction of closet flange.

Fig. 2 is a similar view showing an alternative form of the adjustable packing engaged by the horn of the closet bowl.

Closet bowls and some other plumbing fixtures are usually provided with what is termed a "horn" which projects into the discharge piping and this horn varies in length being sometimes what is termed a "long horn" and again are provided with what is termed a "short horn," the practice varying in different parts of the United States as to this feature as building codes of various cities vary considerably in the requirement for the connection of plumbing fixtures with discharge piping.

In Fig. 1 I have shown the usual discharge piping 1 which has a threaded upper end to receive my improved flange 2. This consists of a substantially cylindrical member having a threaded lower end to engage the piping and a threaded body portion indi-

cated at 3 and terminating with an upper flange 4 offset relative to the body providing an annular recess 5 for a lead packing. Threaded into the body is a cylindrical ring member 6 and on the threaded exterior of this member is provided the threaded flange 7 which is adjustable thereon. This flange is provided with the usual slots and apertures to receive the attaching bolts 8 by means of which the flange 9 of the bowl may be fastened to the adjustable flange 7.

In building construction, the piping is usually installed previous to the finishing of the floors and therefore the main body 2 of my flange is positioned and the surface of this finished floor is above the upper flange end 4 of the said body. By use of the ring member 6, which is threaded in the body, this discharge end may be raised to above the level of the floor (the floor line being indicated at 10 in Fig. 1), and the adjustable flange 7 may be varied thereon so that the bolts 8, on being turned up properly, bind the closet flange 9 to the floor surface. Thus, by use of the adjustable ring and the adjustable flange thereon, my improved flange may accommodate a considerable variation in the positioning of the piping relative to the floor line. This is one of the principal objects of the invention to secure a construction in which the installation of the main pipe may be made without necessity of closely positioning the same to the exact level occupied by the floor surface subsequently laid. Further, by threading the body 3, the piping may be readily plugged after installation for the purpose of testing, and this plug would remain in position until the installation of the plumbing fixtures preventing accumulation of débris in the piping. The flange member and the adjustable flange may be of any approved material as for instance brass while the member 2 may be of wrought iron to receive the cast iron piping 1.

A feature of this invention is in the manner of providing a tight joint between the closet bowl and piping preventing a leakage and for this purpose I provide on the interior of the member 6 a threaded ring like 95

member 11 having an inner peripheral flange 12 as shown in Fig. 1. This member 11 being threaded in the member 6 is adjustable longitudinally of the piping to position to engage the lower end of the horn 13 of the closet bowl. The recess formed between the member 11, flange 12, and horn 13 on the one side and the ring member 6 on the other side may be filled with cement or the like to prevent possibility of leakage. Further, the upper edge of the ring 6 may be beveled as indicated at 14 to receive a packing ring of any approved form, and the adjustment of the member 6 in the member 2 and the adjustment of the flange 7 relative to the member 6 enable the packing to be tightly bound between the point 14 and the closet bowl. Oftentimes a different type of packing is used in the form of a flat ring like member 20 which may lay on the flange 7, and this adjustment with the members 7 and 6 enables a tight joint to be made between the closet bowl and the flange 7.

As before stated, the adjustment of the member 11 enables my improved flange to be utilized with various types of closet bowls and lengths of horn, it only being necessary to position the member 11 so that, upon installation of the bowl end of the horn practically engages the flange 12.

In Fig. 2, the parts are substantially identical with the exception of the ring 11^a which does not have the upwardly extending flange 12 as in the first instance but has a flat upper surface to receive a rubber or compressible ring 15. This ring 15 has the sheet metal brass ring 16 therewithin, the outer diameter of which is slightly less than the inner diameter of the ring 11^a. Thus, with this arrangement the ring 11 may be approximately positioned and the packing ring 15 dropped thereon and the closet bowl positioned, the horn to a greater or less extent compressing the member 15 and carrying the ring member 16 downward within the ring 11^a. This forms an efficient packing between the adjustable ring and the horn and the interstice indicated in Fig. 2 at 17 and may also be filled with a cement. In other respects the structures of Figs. 1 and 2 are identical.

From the foregoing description it will be evident that my improved closet flange is adapted uniformly for use with various types of closet bowl and accommodates variations in height of floor surfaces relative to the discharge piping as is above more particularly described, and that the various objects of the invention are secured by a structure that is simple and inexpensive in form and of a character enabling it to be adjusted to meet the various inaccuracies arising in the installation of the piping.

Having thus briefly described my invention, what I claim is—

1. A closet flange for connecting a closet bowl to a discharge conduit, comprising a tubular body adapted for attachment at one end to the discharge conduit, a cylindrical member fitting the tubular body adjustable longitudinally thereof, a flange carried at the inlet end of the cylindrical member for attachment to the closet bowl base, said cylindrical member being internally threaded, a ring in threaded engagement with the cylindrical member, a compressible packing of ring like form supported on the ring and having a sheet metal tubular member loosely fitting therewithin, the tubular member being of less diameter than the ring whereby, when the closet bowl is secured to the flange, the horn thereof engages the packing supported on the adjustable ring.

2. In a flange for connecting a closet bowl to a discharge conduit, a tubular member having associated therewith in the interior a ring adjustable longitudinally of the axis of the body toward or from the horn of the bowl projecting thereinto, a compressible packing ring supported on the adjustable ring and engaged by the end of the horn when the bowl is secured to the body, said compressible ring having mounted therewithin, and a sheet metal tubular member less in external diameter than the internal diameter of the adjustable ring and extending therethrough.

3. The combination with a closet bowl having a base, a central horn and a recess in the base surrounding the horn, of a flange in the recess, means for securing the flange therein, the said flange having a central threaded aperture, an externally threaded sleeve with the exterior of which the flange is in threaded relation and within the end of which the horn extends, a discharge fitting in threaded relation with the sleeve, a ring member in threaded relation with the interior of the sleeve, and a packing between the ring and the end of the horn.

4. The combination with a closet bowl having a base, a discharge orifice, a horn and a recess surrounding the horn, of a flange located in the said recess and having a central threaded aperture for the horn and a fitting connected therewith comprising an internally threaded body, a sleeve externally threaded to fit the body at one end, the opposite end extending into the recess in threaded engagement with the flange aperture, and into which the horn extends, a ring in threaded relation internally of the sleeve, and a packing held in engagement with the end of the horn by the said ring.

5. The combination with a closet bowl having a base, a horn and a recess about the horn, of a flange located in the recess of the base, means for attaching the flange to the base, said flange having a central internally threaded hub and a fitting for connection

with the bowl comprising an internally threaded body adapted for attachment to a discharge conduit at one end and at the opposite end having a recess for the hub of the flange, a packing in the recess, a sleeve externally threaded for engagement with the fitting and having an end extending in the recess in threaded engagement with the flange hub, said sleeve being internally threaded, a ring within the sleeve in threaded relation therewith, and a packing between the end of the horn and the ring. 10

In testimony whereof, I sign this specification.

EDWARD W. N. BOOSEY.
